(57) **CLAIM**

The ornamental design of a charging station, as shown.

DESCRIPTION

FIG. 1 is a perspective view showing the ornamental design of a charging station in accordance with the invention;

FIG. 2 is a front view of the embodiment of FIG. 1;

FIG. 3 is a side view of the embodiment of FIG. 1;

FIG. 4 is a reverse side view of the embodiment of FIG. 1;

FIG. 5 is a rear view of the embodiment of FIG. 1;

FIG. 6 is a top view of the embodiment of FIG. 1; and,

FIG. 7 is a bottom view of the embodiment of FIG. 1.

The broken lines in the drawings are for the purpose of illustrating unclaimed portions of the battery charger for electric cars and form no part of the claimed design.

1 Claim, 7 Drawing Sheets
